US00D875512S

(12) **United States Design Patent** (10) Patent No.: **US D875,512 S**
 Uchida et al. (45) Date of Patent: **** Feb. 18, 2020**

(54) **FEMALE MEMBER FOR SURFACE FASTENER**

(71) Applicant: **Nitto Denko Corporation**, Osaka (JP)

(72) Inventors: **Shou Uchida**, Osaka (JP); **Shinsuke Ikushima**, Osaka (JP)

(73) Assignee: **Nitto Denko Corporation**, Osaka (JP)

(**) Term: **15 Years**

(21) Appl. No.: **29/546,765**

(22) Filed: **Nov. 25, 2015**

(30) **Foreign Application Priority Data**

May 29, 2015 (JP) 2015-012045

(51) LOC (12) Cl. **08-08**

(52) U.S. Cl.

USPC **D8/382**; D24/189

(57) **CLAIM**

The ornamental design for a female member for surface fastener, as shown and described.

DESCRIPTION

FIG. 1 is a front view of a female member for surface fastener showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a section cut view thereof taken along line 7-7 shown in FIG. 1; and,

FIG. 8 is an enlarged view thereof defined by area 8 shown in FIG. 7.

The portions of the female member for surface fastener shown in broken lines form no part of the claimed design.

1 Claim, 5 Drawing Sheets
